UNITED STATES PATENT OFFICE

113,726

DESIGN FOR A VEGETABLE CHOPPER

Reginald B. Allen, Arden, N. C., assignor of one-half to Charles Searcy

Application September 3, 1938, Serial No. 79,748

Term of patent 3½ years

To all whom it may concern:

Be it known that I, Reginald B. Allen, a citizen of the United States, residing at Arden, in the county of Buncombe and State of North Carolina, have invented a new, original, and ornamental Design for a Vegetable Chopper, of which the following is a specification, reference being had to the accompanying drawing, forming part thereof.

I claim:

The ornamental design for a vegetable chopper, as shown.

REGINALD B. ALLEN.
